UNITED STATES PATENT OFFICE

EDITH A. LARSEN, OF CHICAGO, ILLINOIS

DEVICE FOR ELIMINATING FACIAL WRINKLES

Application filed November 20, 1929. Serial No. 408,607.

This invention relates generally to beautifying devices and more particularly to a device for eliminating facial wrinkles.

After women reach a certain age it often happens that the muscles of the face sag and become weak, causing numerous wrinkles to appear which, they feel, are unsightly. Because of the hazard connected with operations, mechanical devices have been devised for eliminating such wrinkles, which devices employ adhesive or other means adapted to be attached to the skin of the wearer. But the adhesive means, after continual wear, causes a soreness of the skin to which it is attached, or cannot be readily attached or taken off, or, when it is taken off, a part of the adhesive material is left upon the skin which is difficult to remove.

The general object of the invention is to provide a novel device for the elimination of facial wrinkles which is adapted to be attached to the hair adjacent the face to lift the skin of the face, which is at all times comfortable to the wearer even when worn for long periods of time, and which may be readily attached in a concealed position and detached therefrom without leaving undesirable traces of being worn.

Other objects and advantages will become apparent from the following description taken in connection with the accompanying drawing, in which:

Figure 1 is a perspective view of a device embodying the features of the present invention.

Figure 2 is a profile of a head showing the device in place.

Figure 1^a is an end view of the back of one of the combs.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The invention comprises generally resilient means for drawing the skin covering the face of the wearer upwardly and rearwardly, and means for attaching the resilient means to the wearer so that the drawing effect of the resilient means may be transmitted to the skin of the face.

As shown in the drawing, the attaching means comprises a pair of relatively small combs 5 adapted to be inserted into and to grip the hair above and slightly in front of the ears respectively adjacent the temples with the teeth of the combs extending upwardly and rearwardly. The teeth of the combs 5 are relatively long and closely spaced so that they will firmly grip the hair when inserted therein. The combs are preferably curved as illustrated in Fig. 1^a so as to fit snugly over the bone structure of the head and also to fit comfortably and avoid pressing on any nerves in the scalp.

The resilient means or band for drawing the skin covering the face upwardly and rearwardly comprises, in the present instance, an upper head band 7 of resilient material such as elastic and a pair of tapered connecting members 6, made of a fabric such as silk. The connecting members 6 have their wider portions attached to the backs of the combs 5 respectively so that the force of the resilient means will act longitudinally of the combs and will not tend to twist them. The upper head band 7 is attached at its ends to the narrow portions of the connecting members 6 respectively by means of suitable links 8. To permit of adjustment of the length of the band, the part 7 may be formed with a loop on one end and a sliding buckle 9 as is well known in the art. A lower head band 10 may be used, in which case it is detachably attached to the connecting members 6 by means of hooks 11 on the respective ends of the band 10 and eyes on the respective connecting members 6 and is adapted to pass downwardly and rearwardly around the head to assist in positioning and placing a tensioning draw on the combs.

In using the device, the combs 5 are inserted into and firmly grip the hair adjacent the temples with the upper head band pass-

ing over the head and under tension, in the manner shown in Figure 2. Thus, an upward and rearward drawing effect is exerted upon the hair which is transmitted to the 5 scalp and to the skin covering the face, and the wrinkles therein are smoothed out and eliminated. When it is desired to wear the device in public, the hair may be so arranged as to cover the device completely so that it 10 may be entirely concealed. In this case, the lower head band 10 may be worn, or may be detached if it cannot be easily covered by the hair. In wearing the device in private, both bands are used and may be worn over the 15 hair.

It is evident that, because it is attached to the hair and is curved to fit the head, it will cause no soreness to the skin or scalp and will be entirely comfortable to the wearer 20 even when worn for long periods of time. By attaching it to the hair, it may be readily put in place and will leave no undesirable traces when taken off.

I claim as my invention:

25 1. A device for eliminating facial wrinkles comprising, in combination, a pair of relatively small combs adapted to be firmly inserted in the hair of the wearer above and slightly in front of the ears, a pair of tapered fabric connecting members having their wider portions attached to and extending across the width of the combs respectively, an upper resilient head band having its 30 ends connected to the narrower portions of said connecting members respectively and adapted to pass upwardly and rearwardly over the head in longitudinal alinement with said combs to cause said combs to draw on the hair in which they are inserted, means 35 for adjusting the tension of said upper head band, and a lower head band having its ends detachably attached to the connecting members respectively and adapted to pass rearwardly and downwardly around the head 40 45 to assist in positioning and placing a tensioning draw on the combs.

2. A device for eliminating facial wrinkles comprising, in combination, a pair of combs having relatively long closely spaced 50 teeth adapted to be firmly inserted upwardly and rearwardly into and to grip the hair above and slightly in front of the ears on the sides of the head respectively, and resilient means intermediate said combs and attached 55 to said combs along the back thereof adapted to draw upwardly and rearwardly thereon and thereby to draw similarly on the hair and the scalp whereby the skin covering the face is smoothed out and its wrinkles 60 eliminated.

3. A device for eliminating facial wrinkles comprising, in combination, a pair of combs having teeth adapted to be inserted 65 upwardly and rearwardly into and to grip the hair adjacent the temples on each side of

the head respectively and an adjustable resilient band having its ends attached to said combs along the backs thereof respectively and adapted to pass over the head to draw on said combs longitudinally of said teeth, 70 said combs and said band being adapted to be covered by hair to conceal them.

4. A device for eliminating facial wrinkles comprising, in combination, a pair of combs having teeth adapted to be inserted 75 upwardly and rearwardly into and to grip firmly the hair adjacent the temples respectively, and a pair of head bands attached to the backs of said combs and adapted to pass around the head to place a tensioning 80 draw on the combs and make them pull the hair and scalp.

5. A device for eliminating facial wrinkles comprising, in combination, a pair of combs having relatively long closely-spaced 85 teeth adapted to be inserted upwardly and rearwardly into and to grip firmly the hair above and slightly in front of the ears respectively, and resilient means comprising a resilient head band adapted to pass around 90 the head, and a pair of tapered members connecting the ends of said head band with the backs of the combs respectively.

6. A device for eliminating facial wrinkles comprising, in combination, a pair of curved-back combs adapted to be inserted upwardly and rearwardly into the hair and to grip the hair adjacent the temples respectively and to fit snugly against the head without producing a pressure on the nerves 100 of the scalp, and a resilient head band attached at its opposite ends to the backs of said combs and adapted to pass around the head and to draw upwardly and rearwardly thereon so as to place a tensioning draw on 105 the scalp.

In testimony whereof, I have hereunto affixed my signature.

EDITH A. LARSEN.
